UNITED STATES PATENT OFFICE.

GEORGE HAMMER, OF OAKLAND, CALIFORNIA, ASSIGNOR TO HAMMER-BRAY COMPANY, OF OAKLAND, CALIFORNIA, A CORPORATION OF CALIFORNIA.

DESIGN FOR A GAS RANGE.

Application filed February 24, 1926. Serial No. 16,654. Term of patent 14 years.

To all whom it may concern:

Be it known that I, GEORGE HAMMER, a citizen of the United States, and a resident of the city of Oakland, county of Alameda, State of California, have invented a new, original, and ornamental Design for a Gas Range, of which the following is a specification, reference being had to the accompanying drawings, forming part thereof.

The figure is a perspective view of the gas range illustrating my new design.

I claim:

The ornamental design for a gas range, substantially as shown.

GEORGE HAMMER.
